UNITED STATES PATENT OFFICE

121,383

DESIGN FOR A RECEPTACLE FOR FOUNTAIN
PEN OR THE LIKERobert Back, Chicago, Ill., assignor to Eversharp,
Inc., a corporation of Delaware

Application October 6, 1939, Serial No. 87,544

Term of patent 14 years

To all whom it may concern:

Be it known that I, Robert Back, a citizen of the United States, residing at Chicago, in the county of Cook and State of Illinois, have invented a new, original, and ornamental Design for a Receptacle for Fountain Pen or the Like, of which the following is a specification, reference being had to the accompanying drawing forming part thereof, wherein

Fig. 1 is a side elevational view of a receptacle for fountain pen or the like, showing my new design;

Fig. 2 is a rear elevational view of same; and
Fig. 3 is a top and front perspective view of the part shown in full lines in Figs. 1 and 2.

The characterizing features of my design reside in the configuration of the receptacle shown in full lines.

I claim:

The ornamental design for a receptacle for fountain pen or the like, substantially as shown and described.

ROBERT BACK.
